US00D837290S

(12) **United States Design Patent** (10) **Patent No.:** **US D837,290 S**
(45) **Date of Patent:** **** Jan. 1, 2019**

(54) **EMBOSSING MACHINE**

(71) Applicant: **Graphtec Corporation**, Kanagawa (JP)

(72) Inventors: **Takahisa Umezawa**, Kanagawa (JP);
Kazuhiro Watanabe, Kanagawa (JP)

(73) Assignee: **Graphtec Corporation**, Kanagawa (JP)

(**) Term: **15 Years**

(21) Appl. No.: **29/536,243**

(22) Filed: **Aug. 14, 2015**

(30) **Foreign Application Priority Data**

Feb. 23, 2015 (JP) 2015-003607

(51) **LOC (11) Cl.** **18-02**

(52) **U.S. Cl.**

USPC **D18/19**; D15/128; D18/50

(57) **CLAIM**

The ornamental design for an embossing machine, as shown and described.

DESCRIPTION

FIG. 1 is a front view of an embossing machine showing our new design;

FIG. 2 is a rear view thereof;

FIG. 3 is a top plan view thereof;

FIG. 4 is a bottom plan view thereof;

FIG. 5 is a right side view thereof;

FIG. 6 is a left side view thereof; and,

FIG. 7 is a perspective view of front, right and top plan side thereof.

The broken lines immediately adjacent the claim represent the bounds of the claimed design while all other broken lines are directed to environment and are for illustrative purposes only; the broken lines form no part of the claimed design.

1 Claim, 6 Drawing Sheets
